Application August 14, 1939, Serial No. 290,090

8 Claims. (Cl. 179—170)

The present invention relates generally to improvements in signal current transmission systems of the type in which signal controlled switching circuits are provided for partially or completely blocking, under certain conditions, certain of the signal current channels included therein and, more particularly, to improvements in telephone substation circuits having incorporated therein coupled signal current channels for the transmission of incoming and outgoing signal currents.

In the usual telephone substation circuit a hybrid system or antiside tone impedance network is provided for preventing signal currents developed during operation of the transmitter from being transmitted to the receiver and for similarly preventing signal currents incoming over the line extending to the substation from being transmitted to the transmitter for reproduction. In this type of arrangement one of the factors which determines the efficiency of the side tone suppression is the impedance of the talking circuit established by way of two connected subscribers' lines. This impedance is not the same for any two different established connections and, accordingly, the hybrid system of each substation is usually balanced to provide maximum side tone suppression efficiency for average line conditions. In installations wherein amplification of incoming and outgoing signal currents is required, as, for example, in executive loud speaking sets, the conditions of unbalance introduced in the substation circuit by the impedances of the lines over which an established connection extends may become intolerable. This is particularly true in substation installations provided in an exchange area where the subscribers' lines are of widely different lengths. In order completely to obviate or to minimize the singing which may result due to unbalance of the substation circuit occasioned by unfavorable line conditions, signal controlled switching means may be provided in the substation circuit for selectively blocking the channels when not in use. In the usual arrangement of this character the signal channels are completely blocked when not in use. More particularly, during intervals when the transmitting means of the substation is being used to transmit outgoing signal currents, the incoming signal current channel is rendered completely inactive. Conversely, during those periods when signal currents are incoming to the substation, the transmitting or outgoing signal current channel is rendered completely inactive. An arrangement

of this character, while satisfactory in operation, prevents any interruption of a speech train being transmitted in one direction in response to signal currents transmitted in the opposite direction. In other words, conversation break-ins are positively prevented.

It is an object of the present invention to provide improved telephone substation apparatus of the character described wherein the channels are preferably only partially blocked when not in use, the blocking of the signal current transmitting and receiving channels is accomplished in a simple and reliable manner, and wherein the control circuits are arranged to be exceedingly fast in operation so that speech clipping is minimized.

It is another object of the invention to provide an improved transmission system particularly suited for use in telephone substation circuits of the character described wherein the control or channel blocking circuit is arranged in an improved manner to utilize gaseous discharge tubes of the three-electrode type, whereby the circuit is rendered exceedingly fast in operation to effect channel blocking and unblocking operations without any substantial speech clipping.

In each of the three illustrated embodiments of the invention there is provided a telephone substation circuit which is adapted to be connected to an associated line and comprises the usual transmitting and receiving means. The circuit also includes a transmission system which comprises a hybrid or antiside tone impedance network, a first channel for transmitting signal currents from the transmitting means through the hybrid system to the associated line and a second channel for transmitting incoming signal currents from the hybrid system to the receiving means. In accordance with the present invention there is associated with each channel a control circuit comprising a gaseous discharge tube including an anode and a cathode separated to define a space current path and a start electrode for controlling the flow of current over the space current path, together with means controlled by the flow of current over this path for changing the transmission efficiency of at least one of the channels. Apparatus comprising rectifying means is provided for coupling the input electrodes of each of the gaseous discharge tubes to the associated channel so that a predetermined start potential is impressed upon the start electrode of the tube when signal current traverses this signal. As is well known, a tube of this type has an operating characteristic such that

when a space discharge is established between the anode and cathode thereof through the application of a start potential to its start electrode, the start electrode loses control and the arc can only be extinguished by breaking the plate or anode circuit, or by decreasing the potential difference between the anode and cathode below the value required to sustain the discharge. Accordingly, there is provided in each of the two control circuits, circuit means operative to lower the potential difference between the anode and cathode of the associated discharge tube when the flow of signal currents through the associated channel is arrested, thereby to arrest the flow of current over or through the space current path and to restore the control of this path to the start electrode. Two different embodiments of the last-mentioned arc extinguishing means are disclosed. In one of these embodiments a slow-to-release relay is provided in the load or output circuit of the rectifying means, which relay functions momentarily to interrupt the anode circuit of the associated gaseous discharge tube when the input signal voltage derived from the associated channel and impressed upon the input circuit of the rectifying means is removed. In the other embodiment there is locally provided a source of alternating current which is utilized as the anode current source for each of the two discharge tubes. With the latter arrangement, when the start electrode of one of the tubes is biased to the start potential the tube functions as a half wave rectifier so that direct voltages are developed in the output circuit thereof which are utilized to perform the desired channel control functions.

Further features of the invention pertain to the particular arrangement of the circuit elements, whereby the above and additional operating features are attained.

The novel features believed to be characteristic of the invention are set forth with particularity in the appended claims. The invention, both as to its organization and method of operation, together with further objects and advantages thereof will best be understood by reference to the specification taken in connection with the accompanying drawings in which Figure 1 illustrates a substation circuit having incorporated therein certain of the features of the invention as briefly outlined above; Fig. 1a illustrates a slightly different arrangement of certain of the circuit elements shown in Fig. 1; Fig. 2 illustrates a modified form of the substation circuit shown in Fig. 1; and Fig. 3 illustrates a different embodiment of the improved transmission system as incorporated in a substation circuit.

Referring now more particularly to Fig. 1 of the drawings, the substation circuit there illustrated is adapted to be connected to a telephone line terminating at the terminals 100 which may, for example, form a part of a conventional automatic or manual telephone system, in which case, the distant end thereof will terminate in a line circuit the character of which is determined by the character of the exchange. Briefly described, the circuit comprises a transmitter or microphone 101 and receiving means in the form of a loud speaker 102 which are adapted respectively to be coupled to an antiside tone impedance network including a hybrid coil 103 and a balancing circuit 104 by means of signal transmission channels 105 and 106. The outgoing signal current channel 105 comprises a vacuum tube amplifier 108 including three stages of amplification re-

spectively including the amplifier tubes 109, 110 and 111, the first of which is adapted to receive signal currents from the microphone 101 and the last of which is arranged to deliver its output to the hybrid system 103. More particularly, the microphone 101 is coupled to the input electrodes of the first amplifier tube 109 through a coupling network which includes a condenser 112 and an adjustable voltage dividing or signal level control resistor 113. The output electrodes of the tube 109 are coupled to the input electrodes of the succeeding amplifier tube 110 through a resistance capacitance coupling network which includes a pair of resistors 114 and 115 and a coupling condenser 116. Similarly the output electrodes of the second amplifier tube 110 are coupled to the input electrodes of the final amplifier tube 111 through a resistance capacitance coupling network which includes a resistor 117, a voltage dividing or signal level adjusting resistor 118 and a coupling condenser 119. In order to bias the control electrode of the tube 109 to the proper negative potential with respect to the associated cathode, there is provided in the cathode leg of the output circuit of this tube a pair of series connected cathode biasing resistors 120 and 121 which are shunted by a signal current by-pass condenser 122. The control grid of the tube 110 is similarly biased to the proper negative potential with respect to its associated cathode by means of a cathode biasing circuit comprising a resistor 123 shunted by a signal current by-pass condenser 124. A similar cathode biasing network comprising a resistor 125 shunted by a by-pass condenser 126 is included in the cathode leg of the output circuit of the final amplifier tube 111. Anode potentials are supplied to the anodes of the tubes 109, 110 and 111 from a source of anode current, not shown, but having its positive terminal connected to the terminal marked +B, over circuits which respectively include the resistors 114, 117 and certain of the windings of the hybrid coil 103. Screen potentials are impressed upon the screen electrodes of the indicated tubes from the anode current source over paths respectively including filter networks, that leading to the screen electrode of the tube 109 including a resistor 127 and a signal current by-pass condenser 128 and that extending to the screen electrode including a resistor 129 and a by-pass condenser 130.

The incoming signal current transmission channel 106 has included therein an amplifier 135 which includes two stages of amplification 55 respectively comprising the amplifier tubes 136 and 137. More specifically, the incoming signal current terminals of the hybrid coil 103 are coupled to the input electrodes of the first amplifier tube 136 through a coupling network which includes a transformer 138 and an adjustable voltage dividing or signal level control resistor 139. The output electrodes of this tube are coupled to the input electrodes of the second amplifier tube 137 through a resistance capacitance coupling network which comprises a resistor 140, a coupling condenser 141 and an adjustable voltage dividing or signal level control resistor 143. The output electrodes of the second amplifier tube 137 are, in turn, coupled to the voice or signal current coil of the loud speaker 102 through a coupling transformer 144 and a T connected signal current level control resistance network comprising a pair of series resistors 145 and 145' and a shunt resistor 146. In order 70 to bias the control electrode of the tube 137 to

the proper negative potential with respect to the associated cathode, there is provided in the cathode leg of the output circuit of this tube a biasing network which includes a resistor 147 shunted by a signal current by-pass condenser 148. Control of the bias impressed upon the control electrode of the first amplifier tube 136 is effected through the provision of a cathode biasing network which includes a pair of resistors 149 and 150 which are shunted by a signal current by-pass condenser 151. Anode potentials are impressed upon the anode electrodes of the two tubes 136 and 137 from the source of anode current over circuits respectively including a resistor 140 and the primary winding of the coupling transformer 144. Screen potential is impressed upon the screen electrode of the tube 136 from the source of anode current over a path which includes a filter network comprising a resistor 152 and a by-pass condenser 153. Screen potential for the screen anode of the tube 137 is derived in a manner more fully explained subsequently.

In order to control the gains of the amplifiers 108 and 135, thereby to vary the signal current transmission efficiencies of the channels 105 and 106 in accordance with signal current flow therethrough there is provided a control circuit 155 which includes two control units, the first of which operates in response to signal currents traversing the channel 105 and the second of which operates in response to signal currents traversing the channel 106. More particularly, the first unit of the control circuit comprises a gaseous discharge tube 156 of the three-electrode type having an anode 157 and a cathode 158 separated to define a space current path and a control or start electrode 159 interposed therebetween to control the flow of current over the same space current path. The start electrode 159 is normally biased negatively with respect to the cathode 158 over a path which serially includes a resistor 160, a source of bias voltage 161, a resistor 162 and a resistor 163. The space current path of the discharge tube 156 is included in the output circuit of this tube in series with the source of anode potential mentioned above and the resistors 150 and 163, whereby control voltages are developed across these resistors when a discharge through the tube is established, which voltages are utilized to control the final amplifier tube 111 included in the channel 105 and the first amplifier tube 136 included in the channel 106. More particularly, the voltage developed across the two series connected resistors 150 and 163 in response to space current traversing the tube 156 is utilized as the screen potential for the amplifier tube 111, whereby this amplifier tube is only rendered operative to transmit signal currents therethrough in response to a flow of current over the space current path of the tube 156. Since the resistor 150 is also included in the cathode biasing circuit of the amplifier tube 136, the voltage across this resistor also functions to control the signal current gain of the amplifier 135. The two serially connected resistors 160 and 163 are heavily bypassed for signal currents through the provision of a low impedance condenser 164. In order to impress a start potential upon the start grid 159 of the discharge tube 156 when signal currents traverse the channel 105 a rectifying unit is provided which includes a three-electrode vacuum tube 165 having its input electrodes coupled to the channel 105 at a point following the ampli-

20 fier tube 110 and over a circuit which includes a coupling condenser 166. The tube 165 is normally biased to operate as a half wave rectifier by means of a bias battery 167 connected between the input electrodes thereof. The output electrodes of the rectifier tube 165 are included in an output circuit which comprises the two resistors 150 and 162 and the source of anode current connected to the terminal marked +B. In order 25 momentarily to interrupt the output circuit of the gaseous discharge tube 156 when signal current flow over the channel 105 is arrested, there is provided a slow-to-release relay 168 having its winding included in the output circuit of the tube 165 to be energized by space current traversing this tube. This relay is provided with an armature 169 which is arranged to interrupt the output circuit of the discharge tube 156.

20 The second control unit embodied in the control circuit 155, namely, that associated with and responsive to signal currents traversing the channel 106 is essentially identical to that just described and provided in association with the channel 105. More particularly, the second control unit comprises a three-electrode gaseous discharge tube 170 having an anode 171 and a cathode 172 separated to define a space current path and a start electrode 173 interposed in this path for the purpose of controlling the initial flow of current thereover. The output electrodes 171 and 172 of this tube are included in an output circuit which also includes the resistor 121, a second resistor 174 and the source of anode current connected to the terminal marked +B. The voltage developed across these two series connected resistors when space current flows through the tube 170 is utilized as the operating potential for the screen electrode of the amplifier tube 137 included in the channel 106, these two resistors being heavily by-passed for signal currents by a low impedance condenser 175 connected in shunt therewith. Since the resistor 121 forms a part of the cathode biasing circuit for the first amplifier tube 108 included in the outgoing signal current channel 105, the voltage across this resistor serves to determine the gain of the indicated amplifier tube and thus the signal current transmission efficiency of the channel 105. The start electrode 173 of the discharge tube 170 is normally biased negatively with respect to its associated cathode over a path which includes a resistor 176, a source of bias voltage 177, a second resistor 178 shunted by a signal current by-pass condenser 179 and the resistor 174. For the purpose of impressing a start potential upon the start electrode 173 when signal currents traverse the channel 106, a rectifier is provided which comprises a three-electrode vacuum tube 180 having its input electrodes coupled to the channel 106 at a point following the amplifier tube 136 over a circuit including a coupling condenser 181. This tube is normally biased to operate as a half wave rectifier by means of a bias battery 182 connected between the input electrodes thereof. The output electrodes of the tube 180 are included in an output circuit which serially comprises the resistors 121 and 178. In order to control the deionization of the discharge tube 170 there is provided a slow-to-release relay 183 having its operating winding included in the output circuit of the tube 180 and provided with an armature 184 which is operative to make and break the output circuit of the discharge tube 170.

25 30 35 40 45 50 55 60 65 70 75 79 Referring now more particularly to the opera-

tion of the system illustrated in Fig. 1, it is pointed out that in order to condition the signal current channels for signal current transmission, the cathode heater circuit, not shown, for the various tubes illustrated, is first closed. With the apparatus in this condition the amplifier stages respectively comprising the tubes 109, 110 and 136 are all biased to operate at normal gain. Since, however, the two discharge tubes 156 and 170 are at this time in a deionized condition, no screen potentials are available for the screen electrodes of the final amplifier tubes 111 and 137 respectively included in the amplifiers 108 and 135. Thus, both channels are effectively blocked so that no circulation of energy around the system can occur. If, with the apparatus in this condition, a user of the substation circuit speaks into the microphone 101, the resulting signal voltage is impressed upon the input electrodes of the amplifier tube 109 and the amplified output voltage is, in turn, impressed upon the input electrodes of the tube 110. As further amplified by the tube 110 the signal voltage is impressed across the input electrodes of the amplifier stage 111 and also through the condenser 166 across the input electrodes of the rectifier tube 165. During alternate half cycles of this voltage the bias potential impressed upon the control electrode of the tube 165 by the battery 167 is overcome so that space current flows through this tube over a circuit which includes the winding of the relay 168, the resistor 162 and the resistor 150. As indicated above, during signal current transmission through the channel 105, due to the magnitude of the bias impressed across the control electrodes thereof by the battery 167, the vacuum tube 165 functions as a half wave rectifier. Accordingly, a pulsating direct current traverses the space current path of this tube and the resistors 162 and 150. Due to the smoothing action of the condenser 162 shunting the resistor 162, however, the voltage across this resistor does not fall to a zero value during alternate half cycles of signal current but is maintained at a value sufficient to permit ionization of the discharge tube 156. The resulting voltage developed across the resistor 162 is impressed across the input electrodes 158 and 159 of the discharge tube 156 in opposition to the negative bias voltage afforded by the C battery 161. This voltage is of sufficient magnitude to lower the potential of the start grid 159 to a point where a discharge through this tube occurs. When the tube 156 is ionized in this manner, current is caused to traverse the space current path thereof; this current also flowing through the series connected resistors 150 and 163. The last-mentioned resistor has a resistance value substantially greater than that of the resistor 150 and also substantially greater than the resistance of the space current path through the tube 156. Accordingly, a substantial portion of the available voltage of the anode current supply source appears as a voltage drop across the resistor 163. This voltage drop, as augmented by the voltage drop across the resistor 150, is impressed as an operating potential upon the screen electrode of the final amplifier tube 111 included in the channel 105, thereby to render the tube 111 operative to transmit the generated signal currents therethrough and through the hybrid coil 103 to the line terminating at the terminals 100. As indicated above, the operations just described all occur during the first cycle of the signal current developed in response to the sound waves impinging

upon the diaphragm of the microphone 101. Accordingly, no substantial clipping of the first syllable of the speech represented by the sound waves occurs. Simultaneously with the activation 5 of the amplifier tube 111, the first amplifier tube 136 of the channel 106 is either biased to have a very low gain therethrough or beyond cut-off, depending upon the constants of the control circuit. Thus, the current traversing the resistor 150 and flowing through the space current paths 10 of the tubes 156 and 166 causes a voltage to be developed across this resistor which is impressed through the resistor 149 upon the cathode of the tube 136 as a positive bias. This bias voltage has the effect of lowering the gain of the tube 136 and if of sufficiently large magnitude may serve to bias this tube to a point beyond anode current cut-off such that the channel 106 is completely blocked in the first amplifier stage thereof. Alternatively, if the resistance value of the resistor 150 is chosen so that the voltage developed thereacross by the space currents flowing therethrough does not exceed the anode current cut-off value of the tube 136, this tube will pass incoming signal currents to the succeeding amplifier tube 137 at a substantially reduced gain. By virtue of the arrangement just described if the antiside tone network comprising the hybrid coil 103 and the balancing circuit 104 are greatly unbalanced due to the condition of the lines connected to the terminals 100, such that signal currents are transmitted from the channel 105 through this network to the input side of the channel 106, the partial or complete blocking of the latter channel in the first amplifier stage comprising the tube 136 prevents the signal currents from being fed through the channel to initiate operation of the second control unit comprising the rectifier tube 160 and the discharge tube 170. 20

From the foregoing explanation it will be apparent that the current traversing the space current path of the tube 156 as a result of signal voltage impressed upon the input electrodes of this tube also traverses the operating winding of the slow-to-release relay 168. Shortly following the first few cycles of this voltage, the relay 168 operates to break, at its armature 169 and the associated back contact, the previously traced output circuit including the space current path of the discharge tube 156. This circuit is recompleted at the armature 169 and its associated working contact when the armature 169 is moved to its attracted position. During the interval required for operation of the armature 169 from its retracted position to its attracted position the output circuit of the tube 156 is held open. Accordingly, the flow of space current through this tube and through the resistors 150 and 163 is momentarily interrupted, causing the final amplifier tube 111 of the channel 105 momentarily to be rendered inoperative and the bias voltage impressed across the input electrodes of the first amplifier tube 136 included in the channel 106 momentarily to be returned to the normal value. During this operation the potential of the start electrode 159 is maintained at a value permitting the flow of space current through the tube 156 due to the continued operation of the rectifier tube 165. Accordingly, immediately the output circuits of the discharge tube 156 is recompleted at the armature 169 and its associated front contact, space current again flows through the tube 156, thereby to render the final amplifier tube 111 operative and partially or completely to block the signal transmission channel 106. During the

interval when the armature 169 is operating between its two positions no signal current transmission through the channel 105 can occur. Accordingly, a very slight clipping of the intermediate syllables of the speech train may occur during this switching interval. Such clipping is of no consequence, however, since the listener, upon hearing the first syllables of the speech train and the syllables following the interval during which clipping may occur, can readily ascertain, by interpolation, the syllable or partial syllable which is cut off during the switching operation.

When the flow of signal currents through the channel 105 is arrested, the flow of current through the space current path of the rectifier tube 156 is reduced to zero or to a negligible value. Accordingly, the potential impressed upon the start electrode 159 of the discharge tube 156 is increased in a negative sense to a value which will prevent further current flow through this tube after the tube is deionized. As explained above, the character of the discharge tube 156 is such that when ionization therein occurs the start electrode 159 has no further control over the current flow therethrough. Since, however, the operating winding of the relay 168 is de-energized when the flow of signal currents through the channel 105 is arrested, this relay is caused to restore after an interval. During the interval when the armature 169 of the relay 168 is moving between its attracted and retracted positions the output circuit of the discharge tube 156 is interrupted in an obvious manner so that no voltage is available for sustaining the discharge through the tube. Accordingly, the tube 156 is deionized, at which time the control of the space current path in the tube is restored to the negatively biased start electrode 159. Due to the negative potential impressed upon this electrode by the battery 161, ionization of the tube is prevented when the armature 169 is moved into engagement with its associated back contact to again impress the voltage of the anode current source across the anode 157 and the cathode 158. When the space current flow through the two tubes 165 and 156 is interrupted in the manner just explained, the voltage drops across the resistors 150 and 163 are reduced substantially to zero. Accordingly, the operating potential is removed from the screen electrode of the final amplifier tube 111 and this tube is rendered inoperative to transmit signal currents to the hybrid coil 103. Also, the value of the negative bias impressed across the input electrodes of the amplifier tube 136 is decreased to normal so that this amplifier stage is conditioned to operate with normal gain.

The manner in which the second control unit comprising the rectifier tube 180 and the discharge tube 170 functions partially or completely to block the transmission channel 105 and to activate the final amplifier stage of the channel 106 when signal currents are transmitted from the line terminating at the terminals 100 through the hybrid coil 103 to the input side of the channel 106, is substantially identical to the mode of operation of the first control unit as described above. More particularly, signal currents transmitted to the input electrodes of the tube 136 through the coupling transformer 138 and the voltage divider 139 are amplified by this tube and the amplified signal voltage is impressed across the input electrodes of the two tubes 137 and 180. The resulting space current flow through the rectifier tube 180 causes the ioniza-

tion of the discharge tube 170, whereby a relatively heavy current is caused to traverse the control resistors 121 and 174. The voltage drop across these two serially connected resistors is utilized as an operating voltage for the screen electrode of the tube 137, whereby this tube is rendered operative to amplify the signal currents and transmit the same through the transformer 144 and the T connected volume control resistor 145 network to the signal current coil of the loud speaker 102 for reproduction. The voltage developed across the resistor 121 is impressed as a negative bias between the input electrodes of the first amplifier tube 109 included in the channel 105, whereby this tube is either rendered completely inoperative to transmit signal currents therethrough or the gain of the tube is reduced to a very low value. Shortly following the initial flow of signal currents through the channel 106, the slow-to-release relay 183, which is energized by the space current of the tube 180, operates momentarily to extinguish the flow of space current through the discharge tube 170 with the result that the channel 106 is momentarily blocked and the amplifier 109 is momentarily reconditioned to operate with normal gain in the manner described above with reference to signal transmission through the channel 105. During the transmission of signal currents through the channel 106 to the loud speaker 102, the T connected resistance network included in this channel between the coupling transformer 144 and the signal current coil of the loud speaker operates in a well-known manner to maintain the sound output level of the loud speaker substantially constant regardless of changes in the level of the signal currents transmitted to the input side of the channel. When signal current transmission through the channel 106 is arrested the flow of space current through the rectifier tube 180 is arrested. Thus, the operating winding of the relay 183 is deenergized and the potential impressed upon the start electrode 173 of the discharge tube 170 is restored to a negative value which will not permit ionization of the tube after the tube has been deionized. After an interval equal to the release period of the relay 183, the armature 184 is moved from its attracted position to its retracted position. During such movement, the output circuit of the tube 170 is interrupted, thereby to disconnect the source of anode voltage from the anode 171. As a result, the tube is deionized and control of the space current path thereof is restored to the negatively biased start electrode 173. When the flow of space current through the two resistors 121 and 174 is arrested the potential impressed upon the screen electrode of the amplifier tube 137 is reduced substantially to zero, whereby this tube is rendered inoperative. Also, the voltage drop across the resistor 121 is sufficiently reduced to permit the amplifier tube 109 of the channel 105 to operate with substantially normal gain.

The purpose of providing the relays 168 and 183, having slow-to-release characteristics, for controlling the output circuits of the tubes 156 and 170 respectively is to prevent clipping. More particularly, the period or interval required for the release of either of these two relays prevents the blocking of the channels during momentary pauses in signal current transmission through the respective associated channels. To this end, the relay 168, for example, provides a hang-over period, during which the discharge through the tube 156 is sustained, which exceeds the short

pauses occurring in normal speech. Similarly, the slow-to-release period of the relay 183 serves to sustain the flow of space current through the discharge tube 170 for intervals during which short speech pauses may occur.

A modified arrangement for obtaining the delay intervals just described is illustrated in Fig. 1a. The relay arrangement illustrated in this figure may be used in lieu of the relays 168 and 183 as shown in Fig. 1 without changing the armature and contact spring assemblies. In the Fig. 1a arrangement the relay coil comprises a pair of differentially related windings, the lower winding of which is connected in series with a condenser 190 and a resistor 191 across the upper windings. Also, the lower winding is constructed to provide a substantially greater number of ampere turns than the upper winding. With this arrangement included in the circuit of Fig. 1 the initial rush of current through the upper winding occasioned by a flow of space current through the tube 165, for example, causes the relay armature rapidly to be attracted. During such energization, the condenser 190 charges relatively slowly so that the flow of current through the lower winding is relatively low and no substantial opposing action occurs. When the flow of current through the upper winding is decreased or completely arrested, the condenser 190 discharges through the two windings of the relay in series so that the ampere turns represented by the two windings are in aiding phase relation and the armature of the relay is maintained in its attracted position for a short time interval after the current flow through the associated space current path ceases.

If the circuit constants of the circuit illustrated in Fig. 1 are so proportioned that each of the first amplifier stages respectively comprising the tubes 109 and 136 is not completely blocked when the complementary transmission channel is active, the arrangement permits what is known as conversation break-ins to occur. In this regard it will be apparent that signal currents transmitted to the substation circuit over the line connected to the terminals 100 are passed through the hybrid coil 103 to the input side of the channel 106 at a reasonably high intensity as compared with the currents transmitted from the channel 105 to the channel 106 through the hybrid coil during operation of the microphone 101. With the circuit so arranged that the gain of the amplifier stage comprising the tube 136 is only reduced to a low value during signal transmission through the channel 105, the incoming signal currents are transmitted at reduced gain through this first amplifier stage of the channel 106 and are impressed across the input electrodes of the rectifier tube 180, whereby the discharge tube 170 is ionized in the manner previously explained. In response to the flow of space current through the discharge tube 170 the required operating voltage is impressed upon the screen electrode of the amplifier tube 137, thereby to render this tube operative to transmit the incoming signal currents to the loud speaker 102 for reproduction. The activation of the amplifier stage comprising the tube 109 is accompanied by a decrease in the gain of the amplifier stage comprising the tube 109 for reasons which will be apparent from the preceding explanation. After the initial conversation break-in, the user of the illustrated substation circuit is expected to cease speaking, whereby the control unit comprising

75 the rectifier tube 165 and the discharge tube 156 operates to block the channel 105 and to increase the gain through the amplifier stage comprising the tube 136, in the manner pointed out above.

5 In a manner similar to that just described, the user of the substation circuit illustrated may break in upon a speech train being transmitted to the circuit by speaking into the microphone 101 to cause the activation of the channel 105 and a decrease in the gain of the amplifier tube 136, providing the circuit constants of the control circuit 155 are chosen so that the first amplifier stage of the amplifier 108 is not completely blocked when signal currents are being transmitted through the channel 106.

20 While it will be understood that tubes of any desired type having the proper operating characteristics may be used in the circuit illustrated in Fig. 1, preferably, the amplifier tubes 109, 110 and 136 are of the type commercially known as the 6J7G tube; the amplifier tubes 111 and 137 are of the type known as the 25A6G tube; the rectifier tubes 165 and 180 are of the type known as the 6C5G tube; and the gaseous discharge tubes 156 and 170 are of the type commercially known as the 884 tube.

25 The arrangement illustrated in Fig. 2 of the drawings is substantially similar to that shown in Fig. 1, but differs therefrom in that a different method is employed for controlling the gain of the amplifier stages included in the respective channels and a different type of relay arrangement is utilized for controlling the deionization of the two gaseous discharge tubes embodied

30 therein. Due to the similarity between the two circuits, corresponding elements thereof have been identified by reference characters having the same tens and units digits but different hundreds digits respectively corresponding to the two figures.

35 In the arrangement of Fig. 2, the first stage of amplification 209, included in the channel 205 is diagrammatically illustrated and the output electrodes of the last amplifier tube included in this channel are coupled to the outgoing signal current terminals of the hybrid coil 203 through a coupling transformer 285. The control circuit 255 illustrated in Fig. 2 differs from the corresponding circuit 155 illustrated in Fig. 1 in that each of the two relays 268 and 283

40 provided for controlling the deionization of the two discharge tubes 256 and 270, respectively, are double wound relays, the extra winding being arranged to be short-circuited in response to energization of the relay, whereby an additional slow-to-release period is imparted thereto. The two control sections of the circuit are each arranged to control the gain of one amplifier stage in each of the two signal transmission channels. Thus, the control section comprising the rectifier tube 265 and the discharge tube 256, which is coupled to respond to signal currents traversing the channel 205, is arranged to control the bias voltage impressed between the input electrodes of the first amplifier tube 236 included in the channel 206 and the bias voltage impressed between the input electrodes of the amplifier tube 211 included in the channel 205. More particularly, signal voltages developed across the channel 205 at a point following the amplifier tube 210 are impressed upon the input electrodes of the rectifier 265 through a coupling condenser 266.

45 This tube is normally biased to operate as a half wave rectifier by the voltage of the C battery 267 which is connected between the input elec-

50

70

75

trodes of the tube 265 in series with a resistor 286. In order to overcome the bias normally impressed upon the start electrode 259 of the discharge tube 256 by the bias battery 261 when signal currents traverse the channel 205, there is provided in the cathode leg of the output circuit of the rectifier 265 a biasing network which comprises a resistor 287 shunted by a signal current by-pass condenser 288. The load resistors 263 and 260 included in the output circuit of the discharge tube 256 are arranged respectively to control the gains through the amplifier tubes 211 and 236. More particularly, the junction point between these two resistors is grounded and the negative terminal of the anode current source for the tube 256 is connected to the right terminal of the resistor 260. During space current flow through the discharge tube 256 the voltage drop developed across the resistor 263 is impressed through a resistor 289 between the input electrodes of the tube 211 in a direction to overcome the normal negative bias afforded by the C battery 290, thereby to increase the gain of the tube 211. The voltage developed across the resistor 250, on the other hand, is impressed through a filter network which comprises a resistor 291 and a condenser 292, and the voltage divider 299 between the input electrodes of the amplifier tube 236 in a direction to decrease the gain of the last-mentioned tube. In a similar manner, the control voltages developed across the resistors 221 and 274 when space current traverses the discharge tube 270 are utilized reversely to vary the gains through the amplifier tubes 210 and 237, the voltage developed across the resistor 221 being impressed in a negative sense between the input electrodes of the tube 210 through a filter network which comprises a resistor 293 and a condenser 294, and the voltage developed across the resistor 274 being impressed in a positive sense between the input electrodes of the tube 237 through a resistor 295. As illustrated in the drawings, the rectifier tube 280 is coupled through a condenser 281 to be controlled by signal currents traversing the channel 206, the input electrodes of this tube being biased substantially to the anode current cut-off point through the provision of a source of bias voltage 282 which is connected across the input electrodes of the tube 280 in series with a resistor 296. In this unit the control voltage for overcoming the bias voltage of the battery 277, thereby to condition the discharge tube 270 for ionization, is developed across a resistor 297 which is included in the cathode leg of the output circuit of the rectifier tube 280 and is shunted by a smoothing condenser 298.

The mode of operation of the arrangement illustrated in Fig. 2 is, in general, substantially similar to that described above with reference to the arrangement shown in Fig. 1. More particularly, with the cathode heater circuits of the various tubes illustrated in Fig. 2 energized the amplifier stage 209 and the amplifier stages respectively comprising the tubes 210 and 236 are conditioned to operate with normal gain. The two amplifier tubes 211 and 237, on the other hand, are normally biased beyond cut-off by the voltages of the batteries 290 and 299 respectively. Thus, the two channels 205 and 206 are normally completely blocked so that the system is positively prevented from oscillating. With the apparatus in this condition, if sound waves impinge upon the diaphragm of the microphone 201, the

resulting signal currents are amplified in the amplifier stage 209 and are delivered to the input circuit of the second amplifier tube 210. The amplified signal voltages appearing across the output circuit of this second tube are impressed across the input electrodes of the third amplifier tube 211 and also across the input electrodes of the rectifier tube 265. The resulting space current flow through the tube 265 causes a voltage to be developed across the resistor 287 which reduces the negative potential upon the start electrode 259 of the discharge tube 256 to a point where this tube becomes ionized and current flows through the two load resistors 260 and 263. The voltage developed across the resistor 263 opposes the voltage of the C battery 290 and is of such magnitude that the bias between the input electrodes of the tube 211 is sufficiently reduced to permit this tube to operate with normal gain. Accordingly, the amplified signal currents delivered to the input electrodes of the amplifier tube 211 are amplified therein and transmitted through the coupling transformer 285 and the hybrid coil 203 to the line extending to the terminals 200. The voltage developed across the resistor 250, on the other hand, is impressed as a negative bias voltage between the input electrodes of the amplifier tube 236, thus reducing the gain of this tube. By suitably proportioning the resistance value of the resistor 250, the voltage developed thereacross when space current traverses the discharge tube 256 may be proportioned to bias the tube 236 beyond cut-off such that the channel 206 is completely blocked, or to bias this tube so that it operates with only a small gain, whereby only signal currents of substantial magnitudes may be transmitted therethrough. By thus reducing the gain of the amplifier tube 236, signal currents which may be transmitted through the hybrid system 203 to the input side of the channel 206, due to an unbalanced condition of the hybrid system, are prevented from initiating the operation of the control unit comprising the rectifier tube 280 and the discharge tube 270. The relay 268 included in the output circuit of the rectifier 265 functions, in the exact manner previously explained with reference to the corresponding relay of Fig. 1, momentarily to break the space current path of the discharge tube 256 shortly following the initial signal current flow over the channel 205. During its operating period, therefore, the relay 268 momentarily blocks the transmission of signal currents through the channel 205 and increases the gain of the amplifier 236 to its normal value. When, however, the relay 268 is fully operated, the ionized condition of the tube 256 is reestablished, whereby the channel 205 is again rendered operative and the gain of the amplifier tube 236 is again reduced to an exceedingly low value. Upon operating, the relay 268 completes, at its armature 269', an obvious path for short-circuiting its upper winding, thereby to render itself exceedingly slow to release in a manner well understood in the art. By virtue of this arrangement, delay or hang-over periods are provided to prevent the blocking of the channel 205 and the unblocking of the channel 206 during the short intervals which occur between speech syllables.

When the flow of signal currents through the channel 205 is arrested, space current flow through the rectifier tube 265 ceases. As a result, the relay 268 is deenergized and the potential upon the start electrode 259 is restored to a

value which will prevent space current flow through the tube 256 after this tube is deionized. After an interval determined by the release period of the relay 268, this relay restores to interrupt, at its armature 269', the path short-circuiting its upper winding, thereby to render itself reasonably fast to operate. At its armature 269, the relay 268 momentarily interrupts the output circuit of the discharge tube 256, whereby this tube is deionized and control of the space current flow therethrough is restored to the start grid 259. When the flow of space current through the tube 256 is arrested, the voltage drops across the resistors 263 and 250 are reduced to values such that the amplifier tube 211 is biased beyond anode current cut-off and the amplifier tube 236 is biased to operate with normal gain.

The mode of operation of the control unit comprising the rectifier tube 288 and the discharge tube 270 and associated with the channel 206 is identical with that just described with reference to the unit associated with the channel 205. From the foregoing explanation it will be apparent that if the resistors 250 and 221 are properly proportioned so that the associated amplifier tubes 236 and 210 are not biased beyond cut-off when space current traverses these resistors, each of the two channels 205 and 206 is partially active when the other channel is in use. Accordingly, conversation break-ins may occur in a manner which will be apparent from the above description. In this regard it will be apparent that in the usual installation complete blocking of each channel when the other channel is in use is not required in order to prevent singing due to the substantial side tone suppression achieved through operation of the hybrid system 203.

Referring now more particularly to Fig. 3 of the drawings, the embodiment of the invention there illustrated is, in general, quite similar to the circuit shown in Figs. 1 and 2. Accordingly, reference characters having the same tens and units digits but different hundreds digits have been used to identify corresponding elements of the three circuits. From an inspection of the Fig. 3 arrangement it will be apparent that the channel amplifiers 308 and 335 respectively included in the incoming and outgoing signal current transmission channels 305 and 306 are substantially identical in arrangement with the corresponding amplifiers shown in Fig. 2. The control circuit 355 embodied in the arrangement of Fig. 3 is, however, substantially different from that shown in either Figs. 1 or 2. Briefly described, the control circuit 355 comprises a pair of control sections respectively associated with the two channels and individually including three-electrode gaseous discharge tubes 360 and 361 arranged respectively to be controlled by rectifier units 362 and 363. More particularly, a half wave rectifier circuit serially comprising the rectifier 362, a coupling condenser 364, a resistor 365 shunted by a smoothing condenser 366, and a resistor 367 shunted by a smoothing condenser 368, is connected across the output circuit of the amplifier tube 310. The voltage developed across the resistor 365 when signal currents traverse the channel 305 is impressed through a resistor 369 between the input electrodes of the gaseous discharge tube 360 in opposition to the negative bias voltage normally impressed between these electrodes by a bias battery 370 through a resistor 371. The output

5 circuit of the discharge tube 360 includes the resistor 367 and an additional resistor 372 which is shunted by a by-pass condenser 373. This latter resistor is connected in the manner illustrated to control the bias between the input electrodes of the amplifier tube 336 included in the transmission channel 306. The resistor 367, on the other hand, is connected over a path including a C battery 374 and a resistor 375 to control the bias between the input electrodes of the amplifier tube 311.

10 The rectifier unit 363 is similarly included in a circuit bridged across the output circuit of the amplifier tube 336. This circuit also includes a coupling condenser 374, a resistor 375 shunted by a smoothing condenser 376 and a second resistor 377 shunted by a by-pass condenser 378. The voltage developed across the resistor 375 when signal currents traverse the channel 306 is applied to the start electrode of the discharge tube 361 through a resistor 379 in opposition to the negative bias voltage normally impressed upon this electrode by a bias battery 380 through a resistor 381. The voltage developed across the resistor 377 is utilized to oppose the negative bias voltage normally impressed across the input electrodes of the tube 337 by a bias battery 382 which is connected to the control grid of the indicated tube through a resistor 383. The output circuit of the discharge tube 361 includes, in addition to the resistor 377, a second resistor 384 which is shunted by an alternating current by-pass condenser 385. Anode current is supplied to the two discharge tubes 360 and 361 from a source of alternating current 386 having its output terminals coupled to the primary winding of a transformer 387 which includes two secondary sections 388 and 389 respectively included in the output circuits of the discharge tubes 360 and 361.

15 With the circuit of Fig. 3 conditioned for operation, the two discharge tubes 360 and 361 are deionized such that no current traverses the output circuits thereof. Under these conditions, the negative voltage impressed upon the control electrode of the tube 311 by the battery 374 serves to bias this tube beyond anode current cut-off. Similarly, the battery 382 normally serves to bias the amplifier tube 337 beyond cut-off. Accordingly, the two channels 305 and 306 are normally blocked to prevent the passage of signal or noise currents therethrough, whereby local oscillation of the system is prevented. Since no current is traversing the output circuit of the tube 360, the voltage developed across the resistor 372 is relatively low, being of a value such that the amplifier tube 336 is conditioned to operate with normal gain. Similarly, the voltage across the resistor 384 is relatively low, being of a magnitude such that the amplifier tube 310 is conditioned to operate with normal gain. With the apparatus in this condition, if sound waves impinge upon the diaphragm of the microphone 301 the resulting signal voltage as amplified by the two amplifier stages 308 and 310 are impressed between the input electrodes of the amplifier tube 311 and across the above-traced rectifying circuit including the rectifier 362 and the resistors 365 and 367. The resulting voltage drop developed across the resistor 365 serves sufficiently to reduce the negative potential of the start electrode embodied in the discharge tube 360 to cause space current flow through this tube. By virtue of the alternating character of the anode current supply

source 386, current traverses the space current path and the output circuit of the tube 360 only during alternate half cycles of the supply voltage, whereby a pulsating direct current is caused to traverse the two resistors 367 and 372. This current is smoothed by the smoothing action of the shunt condensers 368 and 373, respectively. The direct voltage developed across the resistor 367 as a result of the space current flow through the tube 360 opposes the bias voltage normally impressed across the input electrodes of the tube 311 and reduces this bias to a point where this tube is conditioned to operate with normal gain. Accordingly, the signal currents transmitted to the input circuit of this tube 10 through the amplifier tubes 309 and 310 are amplified in the tube 311 and delivered through the coupling transformer 385 and the hybrid coil 303 to the line connected to the terminals 300. The negative potential appearing at the left terminal of the resistor 372 is impressed through the voltage divider 339 upon the control grid of the amplifier tube 336. Depending upon the resistance value of the resistor 372, this potential may serve to bias the amplifier tube 336 so that its gain is very low or to bias this tube beyond cut-off, thereby completely to block signal transmission through the channel 306. So long as signal currents traverse the rectifying circuit comprising the rectifier 362, the start electrode 30 of the discharge tube 360 is maintained at a potential such that alternate ionization and de-ionization of the discharge tube occurs during alternate half cycles of the anode current supply source. When, however, signal current transmission through the channel 305 is arrested, the flow of current through the rectifying circuit comprising the rectifier 362 ceases. Accordingly, the potential of the start electrode embodied in the discharge tube 360 is returned to its normal negative value. Thereafter and during the next cycle of the anode supply voltage when the potential of the discharge tube anode is reduced to zero to cause the deionization of the tube, the start electrode embodied in the tube is restored 40 to control by virtue of the negative potential impressed thereon, thereby to prevent further space current flow through this tube. In response to the interruption of space current flow through the tube 360, the voltages across the resistors 372 and 367 are reduced to zero or to very low values such that the amplifier tube 311 is again biased beyond cut-off and the gain of the amplifier tube 336 is restored to normal.

The mode of operation of the other control unit, namely, that comprising the discharge tube 361 and the rectifier circuit comprising the rectifier unit 363, when signal currents traverse the channel 306 is substantially identical to the operation of the unit associated with the channel 60 305 as described above. Accordingly, it is believed that the operation of the second control unit will be apparent without further explanation. It will further be apparent that if the resistance values of the resistors 372 and 384 are proportioned so that the tubes 336 and 310 are not biased beyond cut-off when the complementary signal current channels are in use, conversation break-ins may occur.

From the foregoing explanation it will be apparent that the voltages developed across the load resistors 372 and 384 and respectively utilized to control the amplifier tubes 336 and 310 may have components of alternating current of the frequency of the source 386 included therein. 70 75

Such components would, of course, be delivered through the respective associated channels to the output sides thereof. In order to prevent such voltage components from producing interference, the source 386 is preferably constructed to have an output frequency well above the voice frequency range. For example, this source may comprise an electronic oscillator having an output frequency which may range from five thousand to ten thousand cycles. Further, to prevent the voltage of this source from being amplified in the channel 306 and delivered to the loud speaker 302 during periods when the indicated channel is in use, there is provided in this 15 channel a low pass filter 390 having an upper cut-off frequency of the order of five thousand cycles per second. With respect to the components of current which may be transmitted from the anode current supply source 386 through the channel 305 and the hybrid system 303 to the line terminating at the terminals 300, if the frequency of the source 386 is sufficiently high the attenuation over the lines connecting the circuit illustrated with a distant substation will be so great as to permit only a negligible portion of the currents of this frequency to be delivered to the reproducing means at the distant substation.

If the load resistor 372 included in the output circuit of the discharge tube 360 is chosen of a value such that the amplifier tube 336 is not biased beyond cut-off during signal transmission through the channel 305, signal currents may be transmitted from the output side of this channel through the hybrid coil 303 to the input side of the channel 306. The conditions of unbalance in the hybrid coil 303 might be such that these signal currents as delivered through the tube 336 to the rectifier circuit comprising the rectifier 363 would initiate a discharge through the tube 361, thereby to cause a decrease in the gain through the amplifier 308 and an increase in the gain through the amplifier 335 in the manner previously explained. In order to obviate this possibility the start electrode of the tube 361 may be connected to derive a portion of its bias potential from the output circuit of the tube 360. To this end, any desired portion of the resistor 372 may be included in the biasing circuit for the start electrode of the discharge tube 361. As thus connected, the voltage developed across this portion of the resistor 372 aids the bias voltage normally impressed upon the start electrode of the tube 361 by the battery 380. As a result, the voltage across the resistor 375 required to cause ionization of the discharge tube 361 is substantially increased. By properly proportioning the constants of the circuit elements involved, this increase in the voltage required to trip the tube 361 may be sufficient to prevent ionization of this tube in response to signal currents delivered from the channel 305 to the channel 306 through the coupling afforded by the hybrid coil 303, without being so great as to prevent the ionization of the tube 361 when signal currents are delivered to the input side of the channel 306 through the hybrid coil 303 from the line connected to the terminals 300. A similar arrangement may be utilized to prevent inadvertent ionization of the tube 360 in the event the conditions imposed by a particular application require such an expedient.

While there has been described what is at present considered to be the preferred embodi-

ment of the invention, it will be understood that various modifications may be made therein, and it is contemplated to cover in the appended claims all such modifications as fall within the true spirit and scope of the invention.

What is claimed is:

1. In a transmission system, a signal current transmission channel, a signal current amplifier in said channel, a control circuit comprising a gaseous discharge tube including an anode and a cathode separated to define a space current path and a start electrode for controlling the flow of current over said path, a source of alternating voltage for delivering current to said space current path, whereby space current flow over said path is automatically maintained only so long as a predetermined start potential is impressed upon said start electrode, means for impressing said start potential upon said start electrode when signal currents traverse said channel, and means controlled by the resulting flow of current over said path for controlling the gain through said amplifier to change the signal current transmission efficiency of said channel.

2. In a transmission system, a signal current transmission channel, a signal current amplifier in said channel, a control circuit comprising a gaseous discharge tube including an anode and a cathode separated to define a space current path and a start electrode for controlling the flow of current over said path, an output circuit serially including said space current path, a source of alternating current and an impedance element, whereby pulsating direct current is caused to traverse said output circuit only when a predetermined potential is impressed upon said start electrode, means for impressing said predetermined potential upon said start electrode when signal currents traverse said channel, and means controlled by the voltage developed across said impedance element for controlling the gain through said signal current amplifier to change the signal current transmission efficiency of said channel.

3. In a transmission system, a signal current transmission channel, a signal current amplifier in said channel, a control circuit comprising a gaseous discharge tube including an anode and a cathode separated to define a space current path and a start electrode for controlling the flow of current over said path, an output circuit serially including said space current path, a source of alternating current and an impedance element, whereby pulsating direct current is caused to traverse said output circuit only when a predetermined potential is impressed upon said start electrode, rectifying means coupled to said channel and including an output circuit for impressing said predetermined potential upon said start electrode when signal currents traverse said channel, and means controlled by the voltage developed across said impedance element for controlling the gain through said signal current amplifier to change the signal current transmission efficiency of said channel.

4. In a transmission system, a pair of channels for transmitting signal currents in different directions, a control circuit comprising a gas disruptive discharge tube including an anode and a cathode separated to define a space current path and a start electrode for controlling the flow of current over said path, a source of alternating voltage for delivering current to said space current path, whereby space current flow over said path is automatically maintained only so long as a pre-

determined start potential is impressed upon said start electrode, means for impressing said start potential upon said start electrode when signal currents traverse one of said channels, a signal current amplifier in the other of said channels, and means controlled by the resulting flow of current over said path for controlling the gain through said amplifier to change the signal current transmission efficiency of the other of said channels.

5. In a transmission system, a pair of channels for transmitting signal currents in different directions, a control circuit comprising a gas disruptive discharge tube including an anode and a cathode separated to define a space current path and a start electrode for controlling the flow of current over said path, an output circuit serially including said space current path, a source of alternating current and an impedance element, whereby pulsating direct current is caused to traverse said output circuit only when a predetermined potential is impressed upon said start electrode, means for impressing said predetermined potential upon said start electrode when signal currents traverse one of said channels, a signal current amplifier in the other of said channels, and means controlled by the voltage developed across said impedance element for controlling the gain through said amplifier to change the signal current transmission efficiency of the other of said channels.

6. In a transmission system, a pair of channels for transmitting signal currents in different directions, a control circuit comprising a gas disruptive discharge tube including an anode and a cathode separated to define a space current path and a start electrode for controlling the flow of current over said path, an output circuit serially including said space current path, a source of alternating current and an impedance element, whereby pulsating direct current is caused to traverse said output circuit only when a predetermined potential is impressed upon said start electrode, rectifying means coupled to one of said channels and including an output circuit for impressing said predetermined potential upon said start electrode when signal currents traverse one of said channels, a signal current amplifier in the other of said channels, and means controlled by the voltage developed across said impedance element for controlling the gain through said amplifier to change the signal current transmission efficiency of the other of said channels.

7. In a transmission system, a pair of channels for transmitting signal currents in different directions, a control circuit comprising a gas disruptive discharge tube including an anode and a cathode separated to define a space current path and a start electrode for controlling the flow of current over said path, an output circuit serially including said space current path, a source of alternating current and a pair of impedance elements, whereby pulsating direct current is caused to traverse said output circuit only when a predetermined potential is impressed upon said start electrode, rectifying means coupled to said channel and including an output circuit for impressing said predetermined potential upon said start electrode when signal currents traverse one of said channels, means controlled by the voltage developed across one of said impedance elements for increasing the signal current transmission efficiency of said one channel, and means controlled by the voltage developed across the other of said impedance elements for decreasing the

signal current transmission efficiency of the other of said channels.

8. Telephone substation apparatus comprising transmitting means, receiving means and a hybrid system adapted to be connected to a line extending to said apparatus, a normally active channel for transmitting signal currents from said transmitting means to said hybrid system, a second normally active channel for transmitting signal currents from said hybrid system to said receiving means, means comprising a three electrode gaseous discharge tube having input electrodes coupled to one of said channels and output electrodes coupled to both of said channels for simultaneously increasing the signal current transmission efficiency of said one channel and decreasing the signal current trans-

mission efficiency of the other channel when signal currents traverse said one channel, means comprising a three electrode gaseous discharge tube having input electrodes coupled to said other channel and output electrodes coupled to both of said channels for simultaneously increasing the signal current transmission efficiency of said other channel and decreasing the signal current transmission efficiency of said one channel when signal currents traverse said other channel, and means comprising a source of alternating current commonly coupled to the output electrodes of each of said tubes for extinguishing the space current flow through each of said tubes each time the flow of signal currents through the respective associated channels is arrested.

ROSWELL H. HERRICK.
